CLAIM

The ornamental design for the momentum removable bed for pickup truck, as shown and described.

DESCRIPTION

FIG. 1 is a perspective view of the momentum removable

1 Claim, 8 Drawing Sheets

bed for pickup truck, shown in its setting within a pickup truck, the latter being disclosed in phantom line;

FIG. 2 is a left side view, the right side view being a mirror image thereof;

FIG. 3 is a rear view thereof;

FIG. 4 is a front view thereof;

FIG. 5 is a top plan view thereof; and

FIG. 6 is a bottom plan view thereof;

FIG. 7 is a left side view of a modification to the momentum removable bed for pickup truck, the right side view being a mirror image thereof;

FIG. 8 is a rear view thereof;

FIG. 9 is a front view thereof;

FIG. 10 is a top plan view thereof; and

FIG. 11 is a bottom view thereof;

FIG. 12 is a left side view of a modification to the momentum removable bed for pickup truck, the right side view being a mirror image thereof;

FIG. 13 is a rear view thereof;

FIG. 14 is a front view thereof;

FIG. 15 is a top plan view thereof; and

FIG. 16 is a bottom view thereof;

FIG. 17 is a left side view of a modification to the momentum removable bed for pickup trucks;

FIG. 18 is a rear view thereof;

FIG. 19 is a front view thereof;

FIG. 20 is a top plan view thereof; and,

FIG. 21 is a bottom view thereof.

The broken line showing of the bed of a truck in FIG. 1 is for illustrative purposes only and forms no part of the claimed design.
